AUTOMOBILE TENT

Dolores Morgadanes, New Orleans, La.

Application October 31, 1939, Serial No. 302,236

8 Claims. (Cl. 135—7.1)

This invention relates to the class of tents and canopies and pertains particularly to improvements in automobile tents or portable dressing rooms.

At the present time large numbers of automobileists when visiting beach resorts make use of their cars as dressing rooms for changing into and out of swimming clothes. This practice is not only bad for the upholstery and interior 10 finishings of the automobile, but results in the scattering of large amounts of paper and other debris over the beaches or adjacent grounds as it is common practice amongst such motorists to use newspapers or other paper articles to protect, as much as possible, the interior of the 15 motor vehicle. The protection afforded to the interior of the motor vehicle in this manner is very inadequate and in addition to this and the fact that it results in unsightliness of the beach 20 and adjacent grounds, the interior of the vehicle is of such a size that the changing of the clothes therein is a very awkward and uncomfortable process.

The present invention has for its primary object to provide a novel tent or folding dressing room which may be easily and quickly set up against a side of a motor vehicle and securely attached thereto without damage to the finish of the vehicle or without requiring any accessories which must be permanently connected with the machine and which will afford ample protection and room for bathers in changing into and out of swimming clothes, without involving the risk of wetting or otherwise damaging the 35 interior finish of the car.

Another object of the invention is to provide a collapsible auto tent having a frame unit provided with a novel means for coupling it with the body of a motor vehicle in such manner that the 40 setting up and taking down of the tent may be accomplished easily and quickly and does not require the use of any clamps, screws or other such devices for connecting the frame to the body of the vehicle.

Still another object of the invention is to provide a foldable auto tent designed to be attached to one side of a motor vehicle, having an inner wall unit which is employed for covering the adjacent vehicle windows whereby the view into 45 the tent from the opposite side of the vehicle is shut off.

A further object of the invention is to provide a collapsible tent structure having a supporting frame which in addition to being designed for easy and quick attachment to or dis-

connection from the car body, is of an extensible nature whereby the tent may be set up at the side of the vehicle or at the end thereof.

The invention will be best understood from a consideration of the following detailed description taken in connection with the accompanying drawings forming part of this specification, with the understanding, however, that the invention is not to be confined to any strict conformity with the showing of the drawings but 10 may be changed or modified so long as such changes or modifications mark no material departure from the salient features of the invention as expressed in the appended claims.

In the drawings:

Fig. 1 is a view in perspective of the tent structure embodying the invention, showing the same applied.

Fig. 2 is a view in perspective of the frame structure per se.

Fig. 3 is a detail sectional view of one of the attaching cups.

Fig. 4 is a detail view on an enlarged scale of a joint between certain of the frame bars.

Fig. 5 is a sectional view on the line 5—5 of 25 Fig. 2.

Referring now more particularly to the drawings, there is illustrated in Fig. 1 a portion of a motor vehicle of the sedan type, which is indicated generally by the numeral 1 and in association with which the foldable or collapsible tent or dressing room embodying the present invention is shown. The top or roof of this vehicle is indicated at 2, while the near side wall is indicated by the numeral 3.

The foldable tent or dressing room embodying the present invention comprises a top or roof frame 4 which includes two side bars 5. These side bars at one end are joined, as hereinafter specifically described, with the ends of an extensible outer bar which is made up of two slidably joined portions 6 and 7. While any suitable type of connection may be provided between the ends of the side bars 5 and the adjacent ends of the portions of the extensible outer bar, such as will permit the several bars of the frame to be folded up into substantially parallel relation, it is preferred that each of the side bars 5 be provided with a ring 8 and that the outer end of each of the two portions of the outer bar be 40 provided with a similar ring 9 which is joined through the ring 8 in the manner shown so as to form a loose hinge joint.

Each of the portions of the outer extensible bar has secured thereto adjacent its inner end, 55

a slide ring 10 through which the adjacent bar portion extends so that the two bar portions 6 and 7 have their inner ends in overlapped relation and each extends through the slide ring of the other portion, thus permitting the two portions to be shifted longitudinally of one another. While these overlapping ends of the outer bar portions do not slide one within the other, nevertheless, the connection shown forms what might be termed a telescoping joint which permits lengthening or shortening of the outer bar of the frame.

Each of the side bars 5 carries two or more rubber suction cups 11, each of which has a head portion 12 provided with a transverse passage 13 through which the bar 5 passes. These suction cups are adjustable on their supporting bars and are designed for connection with the smooth surface of the top 2 of the motor vehicle. When the suction cups are so attached to the motor vehicle, they will support the rods or bars 5 in a position to extend outwardly from the vehicle top. In the present illustration of the invention, the bars 5 are extended outwardly from the side of the vehicle body and the telescoping or extensible outer bar may be elongated or shortened so as to make the tent of maximum size or of small size as may be desired. By the provision of the extensible outer bar, the tent structure may be reduced in size so that it can be disposed at the rear of the car in which case the bars 5 will extend longitudinally of the car body instead of transversely as shown.

Each of the suction cups 11 has formed integrally therewith a tab or ear 11' which facilitates detaching the cup from the surface of the car body. By this means, it will be readily seen that when it is desired to remove or shift the suction cups, they can be readily disengaged from the car body without danger of injuring the finish such as would be the case if it were necessary to use the finger nail or some instrument to lift the edge of the cup from the surface of the body.

Loosely or hingedly connected with the outer ends of the side bars 5 are brace bars 14 through the medium of the connecting rings 14' which are joined to the rings of the side bars 5 through the medium of the outer bar rings 9, as shown in Fig. 2. The three rings at each outer corner of the frame are thus joined together so that all of the bars may be folded into parallel relation. At the inner end of each brace bar 14 there is provided a suction cup 11'' which, like the cups 11, are provided with edge ears or tabs by which their removal from the surface of the car is facilitated. These brace bars 14 are designed to extend inwardly and downwardly toward the car body when the side bars 5 are disposed horizontally and attached to the roof of the car in the manner shown in Fig. 1, and the suction cups 11'' at the inner ends of the brace bars are secured to the side wall of the car body. These brace bars serve to give support to the outer ends of the side bars 5 and to the outer extensible bar so that these horizontally disposed bars will not sag under the weight of the curtain which they have to support, but if it is preferred, these brace bars 14 may be dispensed with and only the side bars 5 and the two-part extensible outer bar used.

The side bars have joined thereto the side tent curtains 15. The connection between the curtains 15 and the bars is such that the curtains 75 may be readily shifted or slid on the bars and the

top edges of the curtains are joined to a top or roof covering 16. The outer telescoping bar 6-7 also supports a curtain or side wall for the tent structure which is indicated by the numeral 17, and this also may be joined to the top wall 16 5 and to the adjacent edges of the walls 15. It will be obvious, of course, that the material of the outer wall 17 must be of greater fullness than that of the walls 15 so that lengthening of the outer wall bar may be accomplished so as to enlarge the tent to its fullest dimensions and consequently, when the tent is set up in its smallest size, the material of this outer wall will be gathered on the outer bar of the frame.

The inner edges of the walls 15 of the tent 15 body have connected therebetween a panel wall 18 which is placed at the proper height and has the proper width to cover the adjacent windows of the vehicle. This inner or panel wall may be connected to the adjacent edges of the walls 15 20 in any suitable manner so that it may be readily detached when desired as by the use of snap fasteners or other suitable fastening means. By its use entire privacy is given to the interior of the tent structure as it will be impossible for any- 25 one to obtain a view of the inside of the tent through the car windows. This panel wall 18 may be provided with one or more pockets 19 which may be used for holding combs or other toilet accessories or such pockets may, if desired, 30 be placed upon the inner surfaces of the other walls.

When the tent structure is not in use, the side bars 5 of the top or roof frame may be folded in against the outer extensible bar and the brace 35 bars 14 may be folded against the bars 5 and all of the bars then wrapped in the tent material so as to obtain a compact structure which may be easily transported in the motor vehicle.

From the foregoing, it will be readily apparent 40 that there has here been disclosed a collapsible automobile tent which is of simple design and which may be easily and quickly set up for use and which at the same time can be economically constructed and readily transported. 45

What is claimed is:

1. A folding tent supporting structure for attachment to a motor vehicle body, comprising a roof frame defining three sides of a rectangle, means carried by the two opposite sides of the 50 frame adjacent the ends thereof remote from the third side, for securing the said sides at at least two points to the roof of a vehicle whereby the major portion of the frame will extend outwardly from the vehicle for supporting a tent 55 covering.

2. A folding tent supporting structure for attachment to a motor vehicle body, comprising a roof frame defining three sides of a rectangle, means carried by the two opposite sides of the 60 frame at the ends thereof remote from the third side, for attaching the frame solely to the roof of a vehicle whereby the major portion of the frame will extend outwardly from the vehicle for the support of a tent covering, a pair of 65 brace arms each attached to said frame at the side thereof remote from the supporting vehicle body, and means at the other ends of said brace arms for coupling the same with the adjacent wall of the vehicle body. 70

3. A tent supporting structure for attachment to the body of a motor vehicle, comprising a roof frame having a pair of spaced parallel bars and a bar connecting said parallel bars together at one end, said latter bar being in two slidably joined 75

portions, means carried by each of said spaced bars adjacent the ends thereof remote from the two part bar for attaching said pair of bars at at least two points to the roof of a vehicle whereby the major portion of the frame structure is suspended outwardly from the vehicle body for the support of a tent covering, and said attaching means comprising rubber suction cups.

4. A foldable tent supporting structure for connection with a motor vehicle body, comprising a roof frame consisting of a pair of spaced parallel bars and an outer bar connecting said parallel bars together at one end, a pair of rubber suction cups carried upon each of said parallel bars adjacent the end thereof remote from the outer bar and adapted for suction engagement with the roof of the motor vehicle whereby the major portion of the frame will be supported outwardly from the vehicle body for the support of a tent covering.

5. A foldable tent supporting structure for connection with a motor vehicle body, comprising a roof frame consisting of a pair of spaced parallel bars and an outer bar connecting said parallel bars together at one end, a pair of rubber suction cups carried upon each of said parallel bars adjacent the end thereof remote from the outer bar and adapted for suction engagement with the roof of the motor vehicle whereby the major portion of the frame will be supported outwardly from the vehicle body for the support of a tent covering, said outer bar being pivotally joined at its ends to the spaced bars whereby all of the bars may be folded into substantially parallel relation.

6. A foldable tent supporting structure for connection with a motor vehicle body, comprising a roof frame consisting of a pair of spaced parallel

bars and an outer bar connecting said parallel bars together at one end, a pair of rubber suction cups carried upon each of said parallel bars adjacent the end thereof remote from the outer bar and adapted for suction engagement with the roof of the motor vehicle whereby the major portion of the frame will be supported outwardly from the vehicle body for the support of a tent covering, a pair of brace bars each pivotally attached at one end to one of said spaced bars to be folded into parallel relation therewith, and a suction cup carried upon the other end of each brace bar for connection with the wall of the vehicle.

7. A foldable tent structure for attachment to a motor vehicle body, comprising a roof frame resigned to be secured to the vehicle body to extend outwardly therefrom, a tent covering carried by said frame for suspension therefrom and including a top wall and three side walls, two of said side walls having free edges adjacent the vehicle body, and an inner panel wall attached to and connecting said edges and disposed at an elevation and having a width sufficient to cover adjacent window openings of the vehicle body.

8. A folding tent supporting structure for attachment to a motor vehicle body, comprising a roof supporting frame having two elongated side members and a cross member connected between two adjacent ends of the side members, resilient suction means carried by each side member remote from the cross member for attachment to the roof of the vehicle for maintaining the side members extending outwardly from the vehicle, and means coupled with the outer part of the frame remote from said suction means providing a support for said outer part.

DOLORES MORGADANES.
